Attorney.

UNITED STATES PATENT OFFICE.

EDWIN R. PROBERT, OF COVINGTON, KENTUCKY.

SHEET-METAL ROOFING.

1,123,921.

Specification of Letters Patent.

Patented Jan. 5, 1915.

Application filed August 25, 1913. Serial No. 786,419.

To all whom it may concern:

Be it known that I, EDWIN R. PROBERT, a citizen of the United States, and a resident of Covington, in the county of Kenton and State of Kentucky, have invented a certain new and useful Improvement in Sheet-Metal Roofing, of which the following is a specification.

This invention relates to joints for sheet-metal roofing in which overlapped, oppositely-sloping crimps are provided and the fastening-nails are driven through the apex of each lapped joint into the sheathing beneath.

15 The object of the invention herein is to provide within its scope both an ornamental and a plain joint of the oppositely-inclined type, having its capping-member provided with a truncated or flattened apex for the ready insertion of the fastening-nails, and its capped-member with a depressed or concaved apex vertically alined with said truncated or flattened apex for the ready setting and guiding of the nail points, an inclined 20 inner limb extending along one edge of said concaved apex and an L-shape limb extending along the other edge of said concaved apex, the base of said L-shape limb having an upwardly disposed flange to form 25 a gutter to direct any leakage of water in the joint to the eaves below.

Other features of the invention will be hereinafter referred to.

In the accompanying sheet of drawings, 30 Figure 1 is an end elevation of a sheet-metal roofing joint embodying my invention herein in its preferred form that combines the important elements or features most desired in such a roof; and Fig. 2 is a similar 35 view but showing a plain form of my invention herein and with slightly less advantages than those of the somewhat ornamental form seen in Fig. 1.

15 1 indicates that part or edge of the body portion of the sheet containing the upper or capping member of the joint and 2 the opposite edge of the body portion of the contiguous sheet containing the under or capped crimp member of the joint.

20 In Fig. 1, I have shown what is usually designated as an ornamental joint, and, in Fig. 2, a plain or ordinary flat-topped but otherwise inverted-V shape joint is presented to view, both views, however, carrying in 25 their respective structures the really essential features of my invention and adapted

to meet the wants and needs of the trade and user.

In said Fig. 1 the upper or capping crimp-member is composed of a pair of corresponding, inclined sides or limbs 3 and 4, respectively, that extend from and above the plane of the sheet 1 and are integrally-connected by means of a horizontal or truncated apex-member 5. The outer limb 4 of the capping-crimp is somewhat shorter or shallower than the inner limb 3 so that its lower edge shall lie above the plane of the contiguous sheet 2 and thereby reduce seepage into the joint from capillary attraction or otherwise as much as possible without weakening the joint or unduly limiting its closing capacity. The limbs 3 and 4 of the capping-crimp are correspondingly bent or shaped so as to provide for the intermediate, slightly inclined portions 6 and 7, respectively, therein and intended to impart an ornamental appearance or finish to the joint. The horizontal apex-member 5 of the capping crimp-member provides a suitable surface for the ready placing and driving of the fastening-nails, one of the latter being shown at 8 in both views.

In said Fig. 1 the under or capped crimp-member of the joint is composed of an inner inclined limb 9 that projects from the edge of the contiguous sheet 2, a perpendicular outer limb or brace 10, a horizontal connecting apex-member 11 for the upper edges of limbs 9 and 10, a horizontal foot or base 12 projecting outwardly from the lower edge of the perpendicular limb 10, and an upwardly-extending flange 13 along the outer edge of the foot or base 12.

The inner inclined limb 9 is bent so as to form a shoulder 14 that is slightly inclined to coincide with the degree of inclination of the part 7 made in the outer limb 4 of the capping crimp-member. The shoulder 14 lies in a plane somewhat below that of the said part 7 so as to provide an air space 15 for venting and drying purposes and, also, for presenting a positive barrier to the upward seepage of water into the joint by capillary attraction, wind, or otherwise.

The connecting apex-member 11 of the under or capped crimp-member is preferably depressed or made concave, as plainly seen in both views. This concave form enables the ready and accurate locating or seating and direct driving of the nail point therethrough into the sheathing beneath,

and it also provides an air space or vent passage, as well as an auxiliary seepage barrier, below the horizontal apex-member 5 of the upper or capping crimp-member.

5 The perpendicular outer limb 10 of the under crimp-member forms a stiff and rigid support or brace whereby the nailing of the joint in place on the sheathing is greatly facilitated and danger of lateral spreading 10 of the inclined limbs of said joint reduced to a minimum. It is preferable to have the limb 10 taper slightly from the exact perpendicular, as shown in both views, so that the sheets can be more readily nested for 15 storage and shipping and, also, more readily parted when it is desired to use them. In nesting the under or lapped sheets containing the plain form seen in Fig. 2, however, the upwardly-turned flange 13 is turned outwardly, as in the form shown in Fig. 1 and then restored to inwardly-turned position, if desired, when put into use. The lateral foot or base 12 imparts a solid foundation 20 for said perpendicular member 10 and furnishes a suitable bottom for an air or vent 25 passage and a water shed or gutter 16 to direct any possible last or final escape of water over the top of the upright brace 10 in the joint to the eaves below, and thereby 30 prevents any moisture collecting within that part of the joint to cause corrosion.

The upwardly-turned flange 13 along the outer edge of the foot or base 12 completes 35 one side of the gutter or air passage 16 and its outer edge preferably contacts with the inner face of the limb 3 of the capping crimp-member so as to positively strip and direct any leakage or flow of water into the bottom of the gutter to readily flow along 40 it to the eaves below. The flange 13 further aids in supporting the upper crimp-member 3.

In the ornamental form observed in Fig. 1 it will be seen that there is but two flat 45 contacting faces at *a* and *b* between the lapping crimp-members, other points of contact being simply minute and not affecting the joint in the least.

In Fig. 2, I show what is known as a 50 plain joint of the inverted-V type having correspondingly-sloped sides but with a truncated or flat connecting apex. The base portion 1 in this view has a capping crimp-member composed of an inclined plain inner 55 limb 3 and an inclined plain outer limb 4,

with an intermediate integral flat apex-member 5, the said limb 4 being shallower than the limb 3 for the purpose referred to in connection with the description of the same parts in Fig. 1, and the said flat apex- 60 member 5 being also provided the same as in Fig. 1. The base portion 2, however, in the Fig. 2 structure has a slightly different under crimp-member to that shown in Fig. 1, the inclined inner limb 9 being a 65 plain one and coinciding with the plain contacting outer limb 4 of the capping crimp-member.

The depressed or concave apex-member 11 of Fig. 2 and the upright or perpendicular limb or brace 10 with its horizontal foot or base 12 and upwardly-turned flange 13 are all the same as in Fig. 1 excepting that the said flange 13 is flexed nearer to said upright brace 10 and somewhat lessens the 75 area only of the air passage and gutter 16 but without departing from the broad features of the invention herein, as disclosed in Fig. 1, in the least.

The air-space provided above the concave 80 apex-member 11 in Fig. 2 is the first barrier against the onward seepage of water by capillary attraction into the joint, the air-passage 16 also forming a gutter to catch any water that might possibly escape or 85 pass over the top of the upright brace or limb 10 from the chamber and gutter provided by the inner concave apex-member 11.

I claim:

A sheet-metal roofing each of whose sheets 90 or plates has along one longitudinal edge thereof a capping crimp-formation having oppositely-sloping sides that are connected by an intervening flat apex-member and along the other longitudinal edge an under- 95 lying or lapped crimp-formation that has in turn or succession an upwardly-extending inclined limb, then an integral depressed or concaved top or apex portion to form an internal gutter, air-space and nail-hold, 100 then an adjacent apex-supporting perpendicular limb, then an outwardly-extending horizontal foot or base, and then an upwardly-disposed end flange or brace adapted to engage the adjacent inclined member of 105 the capping-crimp.

EDWIN R. PROBERT.
